Primary Examiner — Marie D. Fast Horse**(57) CLAIM**

The ornamental design for a banknote processing device, as shown and described.

DESCRIPTION

FIG. 1 is a front perspective view of a banknote processing device showing our new design;

FIG. 2 is a front elevational view thereof;

FIG. 3 is a rear elevational view thereof;

FIG. 4 is a first side elevational view thereof;

FIG. 5 is an opposite side elevational view thereof;

FIG. 6 is a top plan view thereof; and,

FIG. 7 is a bottom plan view thereof.

The broken lines consisting of uniform dashes and the broken lines consisting of uniform dots both depict portions of the banknote processing device that form no part of the claimed design.
